United States Patent Office.

THOMAS E. WARREN, OF SHELBURNE FALLS, MASSACHUSETTS.

Letters Patent No. 106,099, dated August 2, 1870.

IMPROVEMENT IN ADJUSTABLE GAUGE.

The Schedule referred to in these Letters Patent and making part of the same

To all whom it may concern:

Be it known that I, THOMAS E. WARREN, of Shelburne Falls, in the county of Franklin and State of Massachusetts, have invented an Adjustable Gage or Marker; and I do hereby declare that the following is a full, clear, and exact description thereof, reference being had to the accompanying drawing, and to the letters of reference marked thereon.

Drawing.

Figure 1 is a side elevation of my improved gauge. Figure 2 is a similar view, partly in section.

Figure 3 is a detached view of the gripping-collar of the head-block.

Figure 4 is a top view of the end of the bar that holds the mark-points.

Figure 5 is a transverse section, taken on the line xx of fig. 1.

Similar letters of reference indicate identical parts in each of the figures.

The object of this invention is to provide a gauge which shall be simple, neat, durable, and economical, and, to this end,

It consists in certain peculiarities of construction, combination, and arrangement of the parts composing the same, as will be hereinafter specifically designated and set forth in the following specification and claim.

In the annexed drawing forming a part of this specification—

A is a bar or rod, having a longitudinal slot at one end, as shown in fig. 4, through which plays a traveler, B, having a mark-point secured thereto in any convenient manner, the lower side of the traveler having flanges to act against the under surfaces of the projecting parts of the bar, when drawn up by turning the thumb-nut, b, upon the lug b', attached to the traveler.

A washer may be introduced between the thumb-nut and the bar, if desired. A mark-point, a, is secured to the bar A at the terminus of the slot in said bar, as shown in fig. 2; and

C is the head-block, through which the bar A freely passes. This block is also cut away from one of its sides, so as to admit the gripping-collar D to such an extent as to allow the bar A to pass through it, when the head-block is slid upon the bar.

The collar D has a threaded arm, upon which acts a thumb-nut, E, over a washer, d. The head-block being placed upon the bar, is very firmly secured thereto by turning the thumb-nut.

The advantages are that there may be any number of mark-points, and adjustable to different widths.

The gauge may be used upon regular or irregular surfaces, and also to form circles of different radii, when desired; for the latter purpose the head-block is removed.

I do not claim any of these devices separately considered; but

Having thus described my invention,

What I do claim, and desire to secure by Letters Patent of the United States, is—

The combination of the open slotted bar A, stationary marking-point a, traveler B b', head-block C, collar D, washer d, and thumb-nut E, constructed as shown and described, and for the purpose specified.

In testimony whereof I have hereunto signed my name to this specification, at Shelburne Falls, Franklin county, and State of Massachusetts, in the presence of two attesting witnesses, this 27th day of April, 1870.

THO. E. WARREN.
